CMOS GOA CIRCUIT

CROSS REFERENCE TO RELATED APPLICATIONS

This application is a national stage of PCT Application Number PCT/CN2015/091715 filed on Oct. 12, 2015, claiming foreign priority of Chinese Patent Application No. 201510557210.5 filed on Sep. 2, 2015.

FIELD OF THE INVENTION

The present invention relates to a display technology field, and more particularly to a CMOS GOA circuit.

BACKGROUND OF THE INVENTION

The GOA (Gate Driver on Array) technology, i.e. the array substrate row driving technology is to utilize the array manufacture process of the Thin Film Transistor (TFT) liquid crystal display to manufacture the gate driving circuit on the Thin Film Transistor array substrate for realizing the driving way of scanning the gates row by row. It possesses advantages of reducing the production cost and realizing the panel narrow frame design, and is utilized by many kinds of displays. The GOA circuit has two basic functions: the first is to output the scan driving circuit for driving the gate lines in the panel to activate the TFTs in the display areas and to charge the pixels; the second is the shift register function. When the output of the Nth scan driving signal is accomplished, the output of the N+1th scan driving signal is performed with the control of the clock signal, and the transfer carries on in sequence.

With the development of Low Temperature Poly-Silicon (LTPS) semiconductor thin film transistor, the LTPS TFT liquid crystal display gradually becomes the focus that people pay lots of attentions. Because the silicon crystallization of the LTPS has better order than the amorphous silicon, and the LTPS semiconductor has ultra high carrier mobility, the liquid crystal display utilizing the LTPS TFT possesses advantages of high resolution, fast response speed, high brightness, high aperture ratio and et cetera. Correspondingly, the peripheral circuit around the LTPS TFT liquid crystal panel also becomes the focus that people pay lots of attentions.

FIG. 1 shows a CMOS GOA circuit according to prior art, comprising a plurality of GOA units which are cascade connected. The CMOS GOA circuit according to prior art does not only possess the basic scan driving function and the shift register function but also has a function of raising all the scan driving signals of the respective stages up to high voltage levels at the same time.

N is set to be positive integer, and the Nth GOA unit comprises: an input control module 100, a latch module 300, a signal process module 400 and an output buffer module 500.

The input control module 100 receives a stage transfer signal Q(N-1) of the GOA unit circuit of the former stage, a first clock signal CK1, a first inverted clock signal XCK1, a constant high voltage level signal VGH and a constant low voltage level signal VGL, and is employed to input the signal P(N) which the voltage level is opposite to the stage transfer signal Q(N-1) of the GOA unit circuit of the former stage into the latch module 300;

The latch module 300 comprises a inverter F to invert the signal P(N) and obtains the stage transfer signal of the GOA

2

unit circuit of the Nth stage, and the latch module 300 performs latch to the stage transfer signal Q(N);

The signal process module 400 receives the stage transfer signal Q(N), a second clock signal CK2, the constant high voltage level signal VGH, the constant low voltage level signal VGL and the global signal Gas, and the signal process module 400 is employed to implement NAND logic process to the second clock signal CK2 and the stage transfer signal Q(N) to generate a scan driving signal G(N) of the GOA unit circuit of the Nth stage; implements NOR Logic process to the global signal Gas with a result of implementing AND logic process to the second clock signal CK2 and the stage transfer signal Q(N) to realize that the global signal Gas controls all the scan driving signals G(N) of the respective stages raised up to high voltage levels at the same time. Furthermore, as the global signal Gas is high voltage level, all the scan driving signals G(N) of the respective stages are raised up to high voltage levels at the same time;

The output buffer module 500 is electrically couple to the signal process module 400 and employed to increase a driving ability of the scan driving signal G(N) and to reduce the RC loading in the signal transmission procedure.

In the aforesaid CMOS GOA circuit according to prior art, as achieving the All Gate On function, there is the scan driving signal holding issue. Therefore, the reset and clear process to the voltage level has to be implemented to the stage signal and the scan driving signal before the GOA circuit normal functions. Thus, the GOA unit of the every stage in the CMOS GOA circuit according to prior art further comprises a reset module 200. As shown in FIG. 1, the GOA unit of the Nth stage is illustrated. The reset module 200 further comprises a P-type TFT. The gate of the P-type TFT receives the reset signal Reset, and a source receives a constant high voltage level signal VGH, and a drain is coupled to an input end of the inverter T in the latch module 300. When the reset signal Reset is inputted with a low voltage level, the P-type TFT is conducted, and the inverter F inverts the constant high voltage level signal, and thus pulls down the voltage level of the stage transfer signal Q(N) to clear and reset the stage transfer signal Q(N). The independent reset module 200 can raise the performance of the circuit but the additional components, wirings and signals increase the area of the GOA circuit and raise the complexity of the signals, which makes against the design of narrow frame panel.

Besides, in All Gate On period, except the global signal Gas, the constant high voltage level VGH and the constant low voltage level VGL, all of the rest signals are in floating state to reduce the standby power consumption of the entire circuit. Then, the voltage levels of respective nodes in the circuit are not determined, either. When the GOA circuit reboots and starts to function normally, there is high possibility to cause the failure of the circuit.

SUMMARY OF THE INVENTION

An objective of the present invention is to provide a CMOS COA circuit, which does not only possess the function of raising all the scan driving signals of the respective stages up to high voltage levels at the same time but also can prevent continuation issue of the scan driving signal without utilizing the reset module to reduce the area of the GOA circuit, and raise the stability of the GOA circuit to prevent the failure of the circuit when the GOA circuit reboots and starts to function normally.

For realizing the aforesaid objective, the present invention provides a CMOS GOA circuit, comprising a plurality of GOA units which are cascade connected;

N is set to be positive integer, and the Nth GOA unit comprises: an input control module, a latch module electrically coupled to the input control module, a signal process module electrically coupled to the latch module, an output buffer module electrically coupled to the signal process module and a storage capacitor electrically coupled to the latch module and the signal process module;

the input control module receives a stage transfer signal of the GOA unit circuit of the former N-1th stage, a first clock signal, a global signal, a constant high voltage level signal and a constant low voltage level signal; the input control module comprises a first NOR gate and a second NOR gate; a first input end of the first NOR gate receives the stage transfer signal of the GOA unit circuit of the former N-1th stage, and a second end receives the global signal, and an output end outputs a NOR Logic process result of the stage transfer signal of the GOA unit circuit of the former N-1th stage and the global signal; a first input end of the second NOR gate receives the first clock signal, and a second end receives the global signal, and an output end uses a NOR Logic process result of the first clock signal and the global signal to be a first inverted clock signal to be outputted; the input control module inverts the NOR Logic process result of the stage transfer signal of the GOA unit circuit of the former N-1th stage and the global signal to obtain an inverted stage transfer signal, and inputs the inverted stage transfer signal into the latch module;

the latch module comprises a first inverter, and an input end of the first inverter is inputted with the inverted stage transfer signal, an output end outputs the stage transfer signal; the latch module latches the stage transfer signal;

the signal process module receives the stage transfer signal, a second clock signal, the constant high voltage level signal, the constant low voltage level signal and the global signal, and is employed to implement NAND logic process to the second clock signal and the stage transfer signal to generate a scan driving signal of the GOA unit circuit of the Nth stage; implements NOR Logic process to the global signal with a result of implementing AND logic process to the second clock signal and the stage transfer signal to realize that the global signal controls all the scan driving signals of the respective stages raised up to high voltage levels at the same time;

the output buffer module comprises a plurality of second inverters which are sequentially coupled in series, which are employed to output the scan driving signal and to increase a driving ability of the scan driving signal;

one end of the storage capacitor is electrically coupled to the stage transfer signal, and the other end is grounded, and employed to store a voltage level of the stage transfer signal;

the global signal comprises a single pulse, and as the single pulse is high voltage level, all the scan driving signals of the respective stages are controlled to be raised up to high voltage levels at the same time, and meanwhile, both the first NOR gate and the second NOR gate outputs low voltage levels to control the inverted stage transfer signal to be high voltage level, and the first inverter in the latch module is employed to pull down voltage levels of the stage transfer signals of the respective stages to clear and reset the stage transfer signals of the respective stages.

The input control module further comprises a first P-type TFT, a second P-type TFT, a third N-type TFT and a fourth N-type TFT, which are sequentially coupled in series; a gate of the first P-type TFT receives the first inverted clock

signal, and a source receives the constant high voltage level signal; both gates of the second P-type TFT and the third N-type TFT are coupled to the output end of the first NOR gate; the drains of the second P-type TFT and the third N-type TFT are coupled to each other and output inverted stage transfer signal; a gate of the fourth N-type TFT receives the first clock signal, and a source receives the constant low voltage level signal;

the latch module further comprises a fifth P-type TFT, a sixth P-type TFT, a seventh N-type TFT and an eighth N-type TFT, which are sequentially coupled in series; a gate of the fifth P-type TFT receives the first clock signal, and a source receives the constant high voltage level signal; both gates of the sixth P-type TFT and the seventh N-type TFT receives the stage transfer signal; the drains of the sixth P-type TFT and the seventh N-type TFT are coupled to each other and electrically coupled to the drains of the second P-type TFT and the third N-type TFT; a gate of the eighth N-type TFT receives the first inverted clock signal, and a source receives the constant low voltage level signal;

the signal process module further comprises: a ninth P-type TFT, and a gate of the ninth P-type TFT receives the global signal, and a source receives the constant high voltage level signal; a tenth P-type TFT, and a gate of the tenth P-type TFT receives the stage transfer signal, and a source is electrically coupled to the drain of the ninth P-type TFT, and a drain is electrically coupled to a node; an eleventh P-type TFT, and a gate of the eleventh P-type TFT receives the second clock signal, and a source is electrically coupled to the drain of the ninth P-type TFT, and a drain is electrically coupled to the node; a twelfth N-type TFT, and a gate of the twelfth N-type TFT receives the stage transfer signal, and a drain is electrically coupled to the node; a thirteenth N-type TFT, and a gate of the thirteenth N-type TFT receives the second clock signal, and a drain is electrically coupled to the source of the twelfth N-type TFT, and a source receives the constant low voltage level signal; a fourteenth N-type TFT, and a gate of the fourteenth N-type TFT receives the global signal, and a source receives the constant low voltage level signal, and a drain is electrically coupled to the node.

The output buffer module comprises three second inverters which are sequentially coupled in series, and an input end of the second inverter closest to the signal process module is electrically coupled to the node, and an output end of the second inverter farthest to the signal process module outputs the scan driving signal.

The first inverter is constructed with a fifteenth P-type TFT coupled with a sixteenth N-type TFT in series, and gates of the fifteenth P-type TFT and the sixteenth N-type TFT are electrically coupled to each other to construct the input end of the first inverter and are inputted with the inverted stage transfer signal, and a source of the fifteenth P-type TFT receives the constant high voltage level signal, and a source of the sixteenth N-type TFT receives the constant low voltage level signal, and drains of the fifteenth P-type TFT and the sixteenth N-type TFT are electrically coupled to each other to construct the output end of the first inverter and outputs the stage transfer signal.

The second inverter is constructed with a seventeenth P-type TFT coupled with an eighteenth N-type TFT in series, and gates of the seventeenth P-type TFT and the eighteenth N-type TFT are electrically coupled to each other to construct the input end of the second inverter, and a source of the seventeenth P-type TFT receives the constant high voltage level signal, and a source of the eighteenth N-type TFT receives the constant low voltage level signal,

and drains of the seventeenth P-type TFT and the eighteenth N-type TFT are electrically coupled to each other to construct the output end of the second inverter; an output end of the former second inverter is electrically coupled to an input end of the latter second inverter.

The first NOR gate comprises a nineteenth P-type TFT, a twentieth P-type TFT, a twenty-first N-type TFT and a twenty-second N-type TFT; gates of the twentieth P-type TFT and the twenty-first N-type TFT are electrically coupled to each other to construct the first input end of the first NOR gate and receives the stage transfer signal of the GOA unit circuit of the former N-1th stage; gates of the nineteenth P-type TFT and the twenty-second N-type TFT are electrically coupled to each other to construct the second input end of the first NOR gate and receives the global signal; a source of the nineteenth P-type TFT receives the constant high voltage level signal, and a drain is electrically coupled to a source of the twentieth P-type TFT; both source of the twenty-first N-type TFT and the twenty-second N-type TFT receives the constant low voltage level signal; drains of the twentieth P-type TFT, the twenty-first N-type TFT and the twenty-second N-type TFT are electrically coupled to one another to construct the output end of the first NOR gate and outputs the NOR Logic process result of the stage transfer signal of the GOA unit circuit of the former N-1th stage and the global signal.

The second NOR gate comprises a twenty-third P-type TFT, a twenty-fourth P-type TFT, a twenty-fifth N-type TFT and a twenty-sixth N-type TFT; gates of the twenty-fourth P-type TFT and the twenty-fifth N-type TFT are electrically coupled to each other to construct the first input end of the second NOR gate and receives the first clock signal; gates of the twenty-third P-type TFT and the twenty-sixth N-type TFT are electrically coupled to each other to construct the second input end of the second NOR gate and receives the global signal; a source of the twenty-third P-type TFT receives the constant high voltage level signal, and a drain is electrically coupled to a source of the twenty-fourth P-type TFT; both source of the twenty-fifth N-type TFT and the twenty-sixth N-type TFT receives the constant low voltage level signal; drains of the twenty-fourth P-type TFT, the twenty-fifth N-type TFT and the twenty-sixth N-type TFT are electrically coupled to one another to construct the output end of the second NOR gate and outputs the inverted clock signal.

In the GOA unit of the first stage, the first input end of the first NOR gate receives a circuit start signal.

The second NOR gate comprises a twenty-third P-type TFT, a twenty-fourth P-type TFT, a twenty-fifth N-type TFT and a twenty-sixth N-type TFT; gates of the twenty-fourth P-type TFT and the twenty-fifth N-type TFT are electrically coupled to each other to construct the first input end of the second NOR gate and receives the first clock signal; gates of the twenty-third P-type TFT and the twenty-sixth N-type TFT are electrically coupled to each other to construct the second input end of the second NOR gate and receives the global signal; a source of the twenty-third P-type TFT receives the constant high voltage level signal, and a drain is electrically coupled to a source of the twenty-fourth P-type TFT; both source of the twenty-fifth N-type TFT and the twenty-sixth N-type TFT receives the constant low voltage level signal; drains of the twenty-fourth P-type TFT, the twenty-fifth N-type TFT and the twenty-sixth N-type TFT are electrically coupled to one another to construct the output end of the second NOR gate and outputs the inverted clock signal.

N is set to be positive integer, and the Nth GOA unit comprises: an input control module, a latch module electrically coupled to the input control module, a signal process module electrically coupled to the latch module, an output buffer module electrically coupled to the signal process module and a storage capacitor electrically coupled to the latch module and the signal process module;

the input control module receives a stage transfer signal of the GOA unit circuit of the former N-1th stage, a first clock signal, a global signal, a constant high voltage level signal and a constant low voltage level signal; the input control module comprises a first NOR gate and a second NOR gate; a first input end of the first NOR gate receives the stage transfer signal of the GOA unit circuit of the former N-1th stage, and a second end receives the global signal, and an output end outputs a NOR Logic process result of the stage transfer signal of the GOA unit circuit of the former N-1th stage and the global signal; a first input end of the second NOR gate receives the first clock signal, and a second end receives the global signal, and an output end uses a NOR Logic process result of the first clock signal and the global signal to be a first inverted clock signal to be outputted; the input control module inverts the NOR Logic process result of the stage transfer signal of the GOA unit circuit of the former N-1th stage and the global signal to obtain an inverted stage transfer signal, and inputs the inverted stage transfer signal into the latch module;

the latch module comprises a first inverter, and an input end of the first inverter is inputted with the inverted stage transfer signal, an output end outputs the stage transfer signal; the latch module latches the stage transfer signal;

the signal process module receives the stage transfer signal, a second clock signal, the constant high voltage level signal, the constant low voltage level signal and the global signal, and is employed to implement NAND logic process to the second clock signal and the stage transfer signal to generate a scan driving signal of the GOA unit circuit of the Nth stage; implements NOR Logic process to the global signal with a result of implementing AND logic process to the second clock signal and the stage transfer signal to realize that the global signal controls all the scan driving signals of the respective stages raised up to high voltage levels at the same time;

the output buffer module comprises a plurality of second inverters which are sequentially coupled in series, which are employed to output the scan driving signal and to increase a driving ability of the scan driving signal;

one end of the storage capacitor is electrically coupled to the stage transfer signal, and the other end is grounded, and employed to store a voltage level of the stage transfer signal;

the global signal comprises a single pulse, and as the single pulse is high voltage level, all the scan driving signals of the respective stages are controlled to be raised up to high voltage levels at the same time, and meanwhile, both the first NOR gate and the second NOR gate outputs low voltage levels to control the inverted stage transfer signal to be high voltage level, and the first inverter in the latch module is employed to pull down voltage levels of the stage transfer signals of the respective stages to clear and reset the stage transfer signals of the respective stages;

wherein the input control module further comprises a first P-type TFT, a second P-type TFT, a third N-type TFT and a fourth N-type TFT, which are sequentially coupled in series; a gate of the first P-type TFT receives the first inverted clock signal, and a source receives the constant high voltage level signal; both gates of the second P-type TFT and the third N-type TFT are coupled to the output end of the first NOR

gate; the drains of the second P-type TFT and the third N-type TFT are coupled to each other and output inverted stage transfer signal; a gate of the fourth N-type TFT receives the first clock signal, and a source receives the constant low voltage level signal;

the latch module further comprises a fifth P-type TFT, a sixth P-type TFT, a seventh N-type TFT and an eighth N-type TFT, which are sequentially coupled in series; a gate of the fifth P-type TFT receives the first clock signal, and a source receives the constant high voltage level signal; both gates of the sixth P-type TFT and the seventh N-type TFT receives the stage transfer signal; the drains of the sixth P-type TFT and the seventh N-type TFT are coupled to each other and electrically coupled to the drains of the second P-type TFT and the third N-type TFT; a gate of the eighth N-type TFT receives the first inverted clock signal, and a source receives the constant low voltage level signal;

the signal process module further comprises: a ninth P-type TFT, and a gate of the ninth P-type TFT receives the global signal, and a source receives the constant high voltage level signal; a tenth P-type TFT, and a gate of the tenth P-type TFT receives the stage transfer signal, and a source is electrically coupled to the drain of the ninth P-type TFT, and a drain is electrically coupled to a node; an eleventh P-type TFT, and a gate of the eleventh P-type TFT receives the second clock signal, and a source is electrically coupled to the drain of the ninth P-type TFT, and a drain is electrically coupled to the node; a twelfth N-type TFT, and a gate of the twelfth N-type TFT receives the stage transfer signal, and a drain is electrically coupled to the node; a thirteenth N-type TFT, and a gate of the thirteenth N-type TFT receives the second clock signal, and a drain is electrically coupled to the source of the twelfth N-type TFT, and a source receives the constant low voltage level signal; a fourteenth N-type TFT, and a gate of the fourteenth N-type TFT receives the global signal, and a source receives the constant low voltage level signal, and a drain is electrically coupled to the node;

wherein the first NOR gate comprises a nineteenth P-type TFT, a twentieth P-type TFT, a twenty-first N-type TFT and a twenty-second N-type TFT; gates of the twentieth P-type TFT and the twenty-first N-type TFT are electrically coupled to each other to construct the first input end of the first NOR gate and receives the stage transfer signal of the GOA unit circuit of the former N-1th stage; gates of the nineteenth P-type TFT and the twenty-second N-type TFT are electrically coupled to each other to construct the second input end of the first NOR gate and receives the global signal; a source of the nineteenth P-type TFT receives the constant high voltage level signal, and a drain is electrically coupled to a source of the twentieth P-type TFT; both source of the twenty-first N-type TFT and the twenty-second N-type TFT receives the constant low voltage level signal; drains of the twentieth P-type TFT, the twenty-first N-type TFT and the twenty-second N-type TFT are electrically coupled to one another to construct the output end of the first NOR gate and outputs the NOR Logic process result of the stage transfer signal of the GOA unit circuit of the former N-1th stage and the global signal;

wherein the second NOR gate comprises a twenty-third P-type TFT, a twenty-fourth P-type TFT, a twenty-fifth N-type TFT and a twenty-sixth N-type TFT; gates of the twenty-fourth P-type TFT and the twenty-fifth N-type TFT are electrically coupled to each other to construct the first input end of the second NOR gate and receives the first clock signal; gates of the twenty-third P-type TFT and the twenty-sixth N-type TFT are electrically coupled to each other to

construct the second input end of the second NOR gate and receives the global signal; a source of the twenty-third P-type TFT receives the constant high voltage level signal, and a drain is electrically coupled to a source of the twenty-fourth P-type TFT; both source of the twenty-fifth N-type TFT and the twenty-sixth N-type TFT receives the constant low voltage level signal; drains of the twenty-fourth P-type TFT, the twenty-fifth N-type TFT and the twenty-sixth N-type TFT are electrically coupled to one another to construct the output end of the second NOR gate and outputs the inverted clock signal.

The benefits of the present invention: the present invention provides a CMOS GOA circuit. The first NOR gate and the second NOR gate are located in the input control module. The two input ends of the first NOR gate respectively receives the stage transfer signal of the GOA unit circuit of the former stage and the global signal, and the two input ends of the second NOR gate respectively receives the first clock signal and the global signal. When the global signal is high voltage level, all the scan driving signals of the respective stages are controlled to be raised up to high voltage levels at the same time, and meanwhile, both the first NOR gate and the second NOR gate are controlled to output low voltage levels to control the inverted stage transfer signal to be high voltage level, and the first inverter in the latch module is employed to pull down voltage levels of the stage transfer signals of the respective stages to clear and reset the stage transfer signals of the respective stages. In comparison with prior art, an independent reset module is not required. The additional components, wirings, and reset signal are eliminated to reduce the area of the GOA circuit; besides, by locating the storage capacitor to store the low voltage level of the stage transfer signal when all the scan driving signals of the respective stages are raised up to high voltage levels at the same time. Then, the low voltage level stored by the storage capacitor is utilized to reset the scan driving signals of the respective stages to maintain the scan driving signals of the respective stages at low voltage level to raise the stability of the GOA circuit to prevent the failure of the circuit when the GOA circuit reboots and starts to function normally.

In order to better understand the characteristics and technical aspect of the invention, please refer to the following detailed description of the present invention is concerned with the diagrams, however, provide reference to the accompanying drawings and description only and is not intended to be limiting of the invention.

BRIEF DESCRIPTION OF THE DRAWINGS

The technical solution and the beneficial effects of the present invention are best understood from the following detailed description with reference to the accompanying figures and embodiments.

In drawings,

FIG. 1 is a circuit diagram of a CMOS GOA circuit according to prior art;

FIG. 2 is a circuit diagram of a CMOS GOA circuit according to the present invention;

FIG. 3 is a circuit diagram of a first stage GOA unit in a CMOS GOA circuit according to the present invention;

FIG. 5 is a specific circuit structure diagram of a first NOR gate in an output control module of a CMOS GOA circuit according to the present invention;

FIG. 6 is a specific circuit structure diagram of a second NOR gate in an output control module of a CMOS GOA circuit according to the present invention;

FIG. 7 is a specific circuit structure diagram of a first inverter in a latch module of a CMOS GOA circuit according to the present invention;

FIG. 8 is a specific circuit structure diagram of three second inverters sequentially in series in an output buffer module of a CMOS GOA circuit according to the present invention.

DETAILED DESCRIPTION OF PREFERRED EMBODIMENTS

For better explaining the technical solution and the effect of the present invention, the present invention will be further described in detail with the accompanying drawings and the specific embodiments.

Please refer to FIG. 2 and FIG. 4. The present invention provides a CMOS GOA circuit, comprising a plurality of GOA units which are cascade connected, and the GOA unit of every stage utilizes a plurality of N-type TFTs and a plurality of P-type TFTs, and respective TFTs are all LTPS thin film transistors. N is set to be positive integer, and the Nth GOA unit comprises: an input control module 1, a latch module 3 electrically coupled to the input control module 1, a signal process module 4 electrically coupled to the latch module 3, an output buffer module 5 electrically coupled to the signal process module 4 and a storage capacitor 7 electrically coupled to the latch module 3 and the signal process module 4.

The input control module 1 receives a stage transfer signal Q(N-1) of the GOA unit circuit of the former N-1th stage, a first clock signal CK1, a global signal Gas, a constant high voltage level signal VGH and a constant low voltage level signal VGL. The input control module 1 comprises a first NOR gate Y1 and a second NOR gate Y2; a first input end A of the first NOR gate Y1 receives the stage transfer signal Q(N-1) of the GOA unit circuit of the former N-1th stage, and a second end B receives the global signal Gas, and an output end D outputs a NOR Logic process result of the stage transfer signal Q(N-1) of the GOA unit circuit of the former N-1th stage and the global signal Gas; a first input end A' of the second NOR gate Y2 receives the first clock signal CK1, and a second end B' receives the global signal Gas, and an output end D' uses a NOR Logic process result of the first clock signal CK1 and the global signal Gas to be a first inverted clock signal XCK1 to be outputted. The input control module 1 inverts the NOR Logic process result of the stage transfer signal Q(N-1) of the GOA unit circuit of the former N-1th stage and the global signal Gas to obtain an inverted stage transfer signal XQ(N), and inputs the inverted stage transfer signal XQ(N) into the latch module 3. Specifically, the input control module 1 further comprises a first P-type TFT T1, a second P-type TFT T2, a third N-type TFT T3 and a fourth N-type TFT T4, which are sequentially coupled in series; a gate of the first P-type TFT T1 receives the first inverted clock signal XCK1, and a source receives the constant high voltage level signal VGH; both gates of the second P-type TFT T2 and the third N-type TFT T3 are coupled to the output end D of the first NOR gate Y1; the drains of the second P-type TFT T2 and the third N-type TFT T3 are coupled to each other and output inverted stage transfer signal XQ(N); a gate of the fourth N-type TFT T4 receives the first clock signal CK1, and a source receives the constant low voltage level signal VGL.

Furthermore, the specific circuit structure of the first NOR gate Y1 is shown in FIG. 5 and comprises a nineteenth P-type TFT T19, a twentieth P-type TFT T20, a twenty-first N-type TFT T21 and a twenty-second N-type TFT T22; gates of the twentieth P-type TFT T20 and the twenty-first N-type TFT T21 are electrically coupled to each other to construct the first input end A of the first NOR gate Y1 and receives the stage transfer signal Q(N-1) of the GOA unit circuit of the former N-1th stage; gates of the nineteenth P-type TFT T19 and the twenty-second N-type TFT T22 are electrically coupled to each other to construct the second input end B of the first NOR gate Y1 and receive the global signal Gas; a source of the nineteenth P-type TFT T19 receives the constant high voltage level signal VGH, and a drain is electrically coupled to a source of the twentieth P-type TFT T20; both source of the twenty-first N-type TFT T21 and the twenty-second N-type TFT T22 receives the constant low voltage level signal VGL; drains of the twentieth P-type TFT T20, the twenty-first N-type TFT T21 and the twenty-second N-type TFT T22 are electrically coupled to one another to construct the output end D of the first NOR gate Y1 and outputs the NOR Logic process result of the stage transfer signal Q(N-1) of the GOA unit circuit of the former N-1th stage and the global signal Gas.

The specific circuit structure of the second NOR gate Y2 is shown in FIG. 5 and comprises a twenty-third P-type TFT T23, a twenty-fourth P-type TFT T24, a twenty-fifth N-type TFT T25 and a twenty-sixth N-type TFT T26; gates of the twenty-fourth P-type TFT T24 and the twenty-fifth N-type TFT T25 are electrically coupled to each other to construct the first input end A' of the second NOR gate Y2 and receives the first clock signal CK1; gates of the twenty-third P-type TFT T23 and the twenty-sixth N-type TFT T26 are electrically coupled to each other to construct the second input end B' of the second NOR gate Y2 and receives the global signal Gas; a source of the twenty-third P-type TFT T23 receives the constant high voltage level signal VGH, and a drain is electrically coupled to a source of the twenty-fourth P-type TFT T24; both source of the twenty-fifth N-type TFT T25 and the twenty-sixth N-type TFT T26 receives the constant low voltage level signal VGL; drains of the twenty-fourth P-type TFT T24, the twenty-fifth N-type TFT T25 and the twenty-sixth N-type TFT T26 are electrically coupled to one another to construct the output end D' of the second NOR gate Y2 and outputs the inverted clock signal XCK1.

For the NOR gate, as long as at least one input signal in the two input signals is high voltage level, the output signal is low voltage after NOR logic process. As an illustration, if the global signal Gas received by the second input end B of the first NOR gate Y1 is low voltage level, in condition that the stage transfer signal Q(N-1) of the GOA unit circuit of the former stage received by the first input end A of the first NOR gate Y1 is high voltage levels, the output end D of the first NOR gate Y1 outputs low voltage level, and in condition that the stage transfer signal Q(N-1) of the GOA unit circuit of the former stage received by the first input end A of the first NOR gate Y1 is high voltage levels, the output end D of the first NOR gate Y1 outputs high voltage level; if the global signal Gas received by the second input end B of the first NOR gate Y1 is high voltage level, no matter what voltage level the stage transfer signal Q(N-1) of the GOA unit circuit of the former stage received by the first input end A of the first NOR gate Y1 is, the output end D of the first NOR gate Y1 outputs low voltage level. If the global signal Gas received by the second input end B' of the second NOR gate Y2 is low voltage level, in condition that the first

clock signal CK1 received by the first input end A' of the second NOR gate Y2 is high voltage levels, the first inverted clock signal XCK1 outputted by the output end D' of the second NOR gate Y2 is low voltage level, and in condition that the first clock signal CK1 received by the first input end A' of the second NOR gate Y2 is low voltage levels, the first inverted clock signal XCK1 outputted by the output end D' of the second NOR gate Y2 is high voltage level; if the global signal Gas received by the second input end B' of the second NOR gate Y2 is high voltage level, no matter what voltage level the first clock signal CK1 received by the first input end A' of the second NOR gate Y2 is, the first inverted clock signal XCK1 outputted by the output end D' of the second NOR gate Y2 is low voltage level. In condition that the first NOR gate Y1 outputs high voltage level, and the first clock signal CK1 is high voltage level, the third N-type TFT T3 and the fourth N-type TFT T4 are conducted, and the drain of the third N-type TFT T3 outputs the inverted stage transfer signal XQ(N) of low voltage level; in condition that the first NOR gate Y1 outputs low voltage level, and the first inverted clock signal XCK1 is low voltage level, the first P-type TFT T1 and the second P-type TFT T2 are conducted, and the drain of the second P-type TFT T2 outputs the inverted stage transfer signal XQ(N) of high voltage level.

The latch module 3 comprises a first inverter F1, and an input end K of the first inverter F1 is inputted with the inverted stage transfer signal XQ(N), an output end L outputs the stage transfer signal Q(N). The latch module 3 further comprises a fifth P-type TFT T5, a sixth P-type TFT T6, a seventh N-type TFT T7 and an eighth N-type TFT T8, which are sequentially coupled in series; a gate of the fifth P-type TFT T5 receives the first clock signal CK1, and a source receives the constant high voltage level signal VGH; both gates of the sixth P-type TFT T6 and the seventh N-type TFT T7 receives the stage transfer signal Q(N); the drains of the sixth P-type TFT T6 and the seventh N-type TFT T7 are coupled to each other and electrically coupled to the drains of the second P-type TFT T2 and the third N-type TFT T3; a gate of the eighth N-type TFT T8 receives the first inverted clock signal XCK1, and a source receives the constant low voltage level signal VGL. The specific circuit structure of the first inverter F1 is shown in FIG. 7, and is constructed with a fifteenth P-type TFT T15 coupled with a sixteenth N-type TFT T16 in series, and gates of the fifteenth P-type TFT T15 and the sixteenth N-type TFT T16 are electrically coupled to each other to construct the input end K of the first inverter F1 and are inputted with the inverted stage transfer signal XQ(N), and a source of the fifteenth P-type TFT T15 receives the constant high voltage level signal VGH, and a source of the sixteenth N-type TFT T16 receives the constant low voltage level signal VGL, and drains of the fifteenth P-type TFT T15 and the sixteenth N-type TFT T16 are electrically coupled to each other to construct the output end L of the first inverter F1 and outputs the stage transfer signal Q(N). For the inverter, as the input signal is high voltage level, the output signal is low voltage level, and as the input signal is low voltage level, the output signal is high voltage level. When the first clock signal CK1 is changed to be low voltage level, if the stage transfer signal Q(N) is high voltage level, the seventh N-type TFT T17 and the eighth N-type TFT T18 controlled by the first inverted clock signal XCK1 are conducted. The drain of the seventh N-type TFT T17 outputs low voltage level, i.e. maintains the inverted stage transfer signal XQ(N) to be low voltage level, and the stage transfer signal Q(N) outputted by the first inverter F1 remains to be high voltage level to achieve the latch to the

stage transfer signal Q(N); if the stage transfer signal Q(N) is low voltage level, the sixth P-type TFT T6 and the fifth P-type TFT T5 controlled by the first clock signal CK1 are conducted. The drain of the sixth P-type TFT T6 outputs high voltage level, i.e. maintains the inverted stage transfer signal XQ(N) to be high voltage level, and the stage transfer signal Q(N) outputted by the first inverter F1 remains to be low voltage level to achieve the latch to the stage transfer signal Q(N).

10 The signal process module 4 receives the stage transfer signal Q(N), a second clock signal CK2, the constant high voltage level signal VGH, the constant low voltage level signal VGL and the global signal Gas, and is employed to implement NAND logic process to the second clock signal CK2 and the stage transfer signal Q(N) to generate a scan driving signal G(N) of the GOA unit circuit of the Nth stage; implements NOR Logic process to the global signal Gas with a result of implementing AND logic process to the second clock signal CK2 and the stage transfer signal Q(N) 15 to realize that the global signal Gas controls all the scan driving signals G(N) of the respective stages raised up to high voltage levels at the same time. Specifically, the signal process module 4 comprises: a ninth P-type TFT T9, and a gate of the ninth P-type TFT T9 receives the global signal Gas, and a source receives the constant high voltage level signal VGH; a tenth P-type TFT T10, and a gate of the tenth P-type TFT T10 receives the stage transfer signal Q(N), and a source is electrically coupled to the drain of the ninth P-type TFT T9, and a drain is electrically coupled to a node 20 A(N); an eleventh P-type TFT T11, and a gate of the eleventh P-type TFT T11 receives the second clock signal CK2, and a source is electrically coupled to the drain of the ninth P-type TFT T9, and a drain is electrically coupled to the node A(N); a twelfth N-type TFT T12, and a gate of the twelfth N-type TFT T12 receives the stage transfer signal Q(N), and a drain is electrically coupled to the node A(N); a thirteenth N-type TFT T13, and a gate of the thirteenth N-type TFT T13 receives the second clock signal CK2, and a drain is electrically coupled to the source of the twelfth N-type TFT T12, and a source receives the constant low voltage level signal VGL; a fourteenth N-type TFT T14, and a gate of the fourteenth N-type TFT T14 receives the global signal Gas, and a source receives the constant low voltage level signal VGL, and a drain is electrically coupled to the node A(N). Moreover, when the global signal is low voltage level: in condition that both the second clock signal CK2 and the stage transfer signal Q(N) are high voltage levels, the twelfth N-type TFT T12 and the thirteenth N-type TFT T13 are conducted, and the voltage level of the node A(N) is low voltage level; in condition that both the second clock signal CK2 and the stage transfer signal Q(N) are low voltage levels, the ninth P-type TFT T9, the tenth P-type TFT T10 and the eleventh P-type TFT T11 are conducted, and the voltage level of the node A(N) is high voltage level. When 25 the global signal is low voltage level, no matter what voltage level the second clock signal CK2 and the stage transfer signal Q(N) are, the fourteenth N-type TFT T14 is conducted, and the voltage level of the node A(N) is low voltage level.

30 The output buffer module 5 comprises a plurality of second inverters F2 which are sequentially coupled in series, which are employed to output the scan driving signal G(N) and to increase a driving ability of the scan driving signal G(N). Preferably, the output buffer module 5 comprises three second inverters F2 which are sequentially coupled in series. As shown in FIG. 8, the second inverter F2 is 35 constructed with a seventeenth P-type TFT T17 coupled

with an eighteenth N-type TFT T18 in series, and gates of the seventeenth P-type TFT T17 and the eighteenth N-type TFT T18 are electrically coupled to each other to construct the input end K' of the second inverter F2, and a source of the seventeenth P-type TFT T17 receives the constant high voltage level signal VGH, and a source of the eighteenth N-type TFT T18 receives the constant low voltage level signal VGL, and drains of the seventeenth P-type TFT T17 and the eighteenth N-type TFT T18 are electrically coupled to each other to construct the output end L' of the second inverter F2; the input end K' of the second inverter F2 receives the first clock signal CK1, and the output end L' outputs the first inverted clock signal XCK1; an input end K' of the second inverter F2 closest to the signal process module 4 is electrically coupled to the node A(N), and an output end L' of the second inverter F2 farthest to the signal process module 4 outputs the scan driving signal G(N), and an output end L' of the former second inverter F2 is electrically coupled to an input end K' of the latter second inverter F2. When the voltage level of the node A(N) is low voltage level, the scan driving signal G(N) is high voltage level after the backward acting function of the three second inverters F2 which are sequentially coupled in series in the output buffer module 5; when the voltage level of the node A(N) is high voltage level, the scan driving signal G(N) is low voltage level after the backward acting function of the three second inverters F2 which are sequentially coupled in series in the output buffer module 5.

One end of the storage capacitor 7 is electrically coupled to the stage transfer signal Q(N), and the other end is grounded, and employed to store a voltage level of the stage transfer signal Q(N).

Specifically, the global signal Gas comprises a single pulse, and the single pulse is triggered before the GOA circuit normally functions. When the global signal Gas is high voltage level, the fourteenth N-type TFTs T14 in the GOA unit circuits of respective stages are conducted, the voltage levels of the nodes A(N) in the GOA unit circuits of respective stages are low voltage levels, all the scan driving signals G(N) of the respective stages are raised up to high voltage levels at the same time after the backward acting function of the three second inverters F2 which are sequentially coupled in series in the output buffer module 5 in the GOA unit circuits of respective stages; meanwhile, the global signal Gas of high voltage level controls the first NOR gate Y1 and the second NOR gate Y2 both to output low voltage levels, and the first P-type TFT F1 and the second P-type TFT T2 are conducted, and the drain of the second P-type TFT T2 outputs the inverted stage transfer signal XQ(N) of high voltage level, and the first inverter F1 in the latch module 3 is employed to pull down voltage levels of the stage transfer signals Q(N) of the respective stages to clear and reset the stage transfer signals Q(N) of the respective stages. Then, the storage capacitor 7 stores the low voltage level of the stage transfer signal Q(N). After the function of raising all the scan driving signals G(N) of the respective stages up to high voltage levels at the same time finishes, the global signal Gas is changed to be low voltage level. Because the storage capacitor 7 stores the low voltage level, the ninth P-type TFT T9 and the tenth P-type TFT T10 are conducted, and the voltage level of the node A(N) is changed to be high voltage level. All the scan driving signals G(N) of the respective stages are changed to be low voltage levels at the same time after the backward acting function of the three second inverters F2 which are sequentially coupled in series in the output buffer module 5 in the GOA unit

circuits of respective stages. The continuation issue of the scan driving signal can be prevented. Then, the COMS GOA circuit normally works.

In comparison with prior art, an independent reset module 5 is not required to the aforesaid CMOS GOA circuit. The additional components, wirings, and reset signal are eliminated to reduce the rear of the GOA circuit, and simplify the complexity of the signal, which is beneficial to the design of narrow frame panel. Besides, by locating the storage capacitor 7 to store the low voltage level of the stage transfer signal Q(N) when all the scan driving signals G(N) of the respective stages are raised up to high voltage levels at the same time. Then, the low voltage level stored by the storage capacitor 7 is utilized to reset the scan driving signals G(N) of the respective stages to maintain the scan driving signals G(N) of the respective stages at low voltage level to raise the stability of the GOA circuit to prevent the failure of the circuit when the GOA circuit reboots and starts to function normally.

20 Significantly, as the global signal Gas is high voltage level, both the first clock signal CK1 and the second clock signal CK2 can be in high-impedance state. After the global signal Gas is changed from high voltage level to low voltage level, the first clock signal CK1 advances one pulse width than the second clock signal CK2.

25 Particularly, as shown in FIG. 3, in the GOA unit of the first stage, the first input end A of the first NOR gate Y1 receives a circuit start signal STV. With combination of FIG. 3 and FIG. 4, as the CMOS GOA circuit starts to normally function, the global signal is low voltage level, and the circuit start signal STV is low voltage level, and the first clock signal CK1 is high voltage level, and the first NOR gate Y1 outputs high voltage level, and the second NOR gate Y2 outputs low voltage level, and the third N-type TFT T3 and the fourth N-type TFT T4 are conducted, and the drain of the third N-type TFT T3 outputs the inverted stage transfer signal XQ(1) of low voltage level; the stage transfer signal Q(1) outputted by the first inverter F1 of the latch module 3 is high voltage level, and after the first clock signal CK1 is changed to be low voltage level, the high voltage level of the stage transfer signal Q(1) remains to be latched. Then, as the second clock signal CK2 is high voltage level, the twelfth N-type TFT T12 and the thirteenth N-type TFT T13 are conducted, and the voltage level of the node A(1) is low voltage level; the scan driving signal (1) is high voltage level after the backward acting function of the three second inverters F2 which are sequentially coupled in series in the output buffer module 5. Afterward, the GOA unit of the second stage receives the stage transfer signal Q(1) of the GOA unit of the first stage to perform scan driving and so forth until the GOA unit of the last stage accomplishes the scan driving.

30 In conclusion, in the CMOS GOA circuit of the present invention, the first NOR gate and the second NOR gate are located in the input control module. The two input ends of the first NOR gate respectively receives the stage transfer signal of the GOA unit circuit of the former stage and the global signal, and the two input ends of the second NOR gate respectively receives the first clock signal and the global signal. When the global signal is high voltage level, all the scan driving signals of the respective stages are controlled to be raised up to high voltage levels at the same time, and meanwhile, both the first NOR gate and the second NOR gate are controlled to output low voltage levels to control the inverted stage transfer signal to be high voltage level, and the first inverter in the latch module is employed to pull down voltage levels of the stage transfer signals of the

15

respective stages to clear and reset the stage transfer signals of the respective stages. In comparison with prior art, an independent reset module is not required. The additional components, wirings, and reset signal are eliminated to reduce the area of the GOA circuit; besides, by locating the storage capacitor to store the low voltage level of the stage transfer signal when all the scan driving signals of the respective stages are raised up to high voltage levels at the same time. Then, the low voltage level stored by the storage capacitor is utilized to reset the scan driving signals of the respective stages to maintain the scan driving signals of the respective stages at low voltage level to raise the stability of the GOA circuit to prevent the failure of the circuit when the GOA circuit reboots and starts to function normally.

Above are only specific embodiments of the present invention, the scope of the present invention is not limited to this, and to any persons who are skilled in the art, change or replacement which is easily derived should be covered by the protected scope of the invention. Thus, the protected scope of the invention should go by the subject claims.

What is claimed is:

1. A CMOS Gate Driver on Array (GOA) circuit, comprising a plurality of GOA unit circuits, which are cascade connected as multiple sequentially-arranged stages;

wherein N is set to be positive integer, and the GOA unit circuit of an Nth one of the multiple stages comprises: an input control module, a latch module electrically coupled to the input control module, a signal process module electrically coupled to the latch module, an output buffer module electrically coupled to the signal process module and a storage capacitor electrically coupled to the latch module and the signal process module;

the input control module receives a stage transfer signal of the GOA unit circuit of an N-1th stage, which is one of the multiple stages that is immediately previous of the Nth stage, a first clock signal, a global signal, a constant high voltage level signal and a constant low voltage level signal; the input control module comprises a first NOR gate and a second NOR gate; a first input end of the first NOR gate receives the stage transfer signal of the GOA unit circuit of the N-1th stage, and a second end receives the global signal, and an output end outputs a NOR Logic process result of the stage transfer signal of the GOA unit circuit of the N-1th stage and the global signal; a first input end of the second NOR gate receives the first clock signal, and a second end receives the global signal, and an output end uses a NOR Logic process result of the first clock signal and the global signal to be a first inverted clock signal to be outputted; the input control module inverts the NOR Logic process result of the stage transfer signal of the GOA unit circuit of the N-1th stage and the global signal to obtain an inverted stage transfer signal, and inputs the inverted stage transfer signal into the latch module;

the latch module comprises a first inverter, and input end of the first inverter is inputted with the inverted stage transfer signal, output end outputs the stage transfer signal; the latch module latches the stage transfer signal;

the signal process module receives the stage transfer signal, a second clock signal, the constant high voltage level signal, the constant low voltage level signal and the global signal, and is employed to implement NAND logic process to the second clock signal and the stage transfer signal to generate a scan driving signal of the

16

GOA unit circuit of the Nth stage; implements NOR Logic process to the global signal with a result of implementing AND logic process to the second clock signal and the stage transfer signal to realize that the global signal controls all the scan driving signals of respective stages raised up to high voltage levels simultaneously;

the output buffer module comprises a plurality of second inverters which are sequentially coupled in series, which are employed to output the scan driving signal and to increase a driving ability of the scan driving signal;

one end of the storage capacitor is electrically coupled to a node between the latch module and the signal process module, and the other end is grounded, and employed to store a voltage level of the stage transfer signal; the global signal comprises a single pulse, and as the single pulse is high voltage level, all the scan driving signals of the respective stages are controlled to be raised up to high voltage levels at same time, and meanwhile, both the first NOR gate and the second NOR gate outputs low voltage levels to control the inverted stage transfer signal to be high voltage level, and the first inverter in the latch module is employed to pull down voltage levels of the stage transfer signals of the respective stages to clear and reset the stage transfer signals of the respective stages;

wherein the input control module further comprises a first P-type thin film transistor (TFT), a second P-type TFT, a third N-type TFT and a fourth N-type TFT, which are sequentially coupled in series; a gate of the first P-type TFT receives the first inverted clock signal, and a source receives the constant high voltage level signal; both gates of the second P-type TFT and the third N-type TFT are coupled to the output end of the first NOR gate; the drains of the second P-type TFT and the third N-type TFT are coupled to each other and output inverted stage transfer signal; a gate of the fourth N-type TFT receives the first clock signal, and a source receives the constant low voltage level signal;

the latch module further comprises a fifth P-type TFT, a sixth P-type TFT, a seventh N-type TFT and an eighth N-type TFT, which are sequentially coupled in series; a gate of the fifth P-type TFT receives the first clock signal, and a source receives the constant high voltage level signal; both gates of the sixth P-type TFT and the seventh N-type TFT receives the stage transfer signal; the drains of the sixth P-type TFT and the seventh N-type TFT are coupled to each other and electrically coupled to the drains of the second P-type TFT and the third N-type TFT; a gate of the eighth N-type TFT receives the first inverted clock signal, and a source receives the constant low voltage level signal;

the signal process module further comprises: a ninth P-type TFT, and a gate of the ninth P-type TFT receives the global signal, and a source receives the constant high voltage level signal; a tenth P-type TFT, and a gate of the tenth P-type TFT receives the stage transfer signal, and a source is electrically coupled to the drain of the ninth P-type TFT, and a drain is electrically coupled to a node; an eleventh P-type TFT, and a gate of the eleventh P-type TFT receives the second clock signal, and a source is electrically coupled to the drain of the ninth P-type TFT, and a drain is electrically coupled to the node; a twelfth N-type TFT, and a gate of the twelfth N-type TFT receives the stage transfer signal, and a drain is electrically coupled to the node;

a thirteenth N-type TFT, and a gate of the thirteenth N-type TFT receives the second clock signal, and a drain is electrically coupled to the source of the twelfth N-type TFT, and a source receives the constant low voltage level signal; a fourteenth N-type TFT, and a gate of the fourteenth N-type TFT receives the global signal, and a source receives the constant low voltage level signal, and a drain is electrically coupled to the node.

2. The CMOS GOA circuit according to claim 1, wherein the output buffer module comprises three second inverters which are sequentially coupled in series, and input end of one of the three second inverters directly next to the signal process module is electrically coupled to the node, and output end of the second inverter farthest to the signal process module outputs the scan driving signal.

3. The CMOS GOA circuit according to claim 2, wherein the second inverter is constructed with a seventeenth P-type TFT coupled with an eighteenth N-type TFT in series, and gates of the seventeenth P-type TFT and the eighteenth N-type TFT are electrically coupled to each other to construct the input end of the second inverter, and a source of the seventeenth P-type TFT receives the constant high voltage level signal, and a source of the eighteenth N-type TFT receives the constant low voltage level signal, and drains of the seventeenth P-type TFT and the eighteenth N-type TFT are electrically coupled to each other to construct the output end of the second inverter; an output end of the former second inverter is electrically coupled to input end of a next one of the second inverters.

4. The CMOS GOA circuit according to claim 1, wherein the first inverter is constructed with a fifteenth P-type TFT coupled with a sixteenth N-type TFT in series, and gates of the fifteenth P-type TFT and the sixteenth N-type TFT are electrically coupled to each other to construct the input end of the first inverter and are inputted with the inverted stage transfer signal, and a source of the fifteenth P-type TFT receives the constant high voltage level signal, and a source of the sixteenth N-type TFT receives the constant low voltage level signal, and drains of the fifteenth P-type TFT and the sixteenth N-type TFT are electrically coupled to each other to construct the output end of the first inverter and outputs the stage transfer signal.

5. The CMOS GOA circuit according to claim 1, wherein the first NOR gate comprises a nineteenth P-type TFT, a twentieth P-type TFT, a twenty-first N-type TFT and a twenty-second N-type TFT; gates of the twentieth P-type TFT and the twenty-first N-type TFT are electrically coupled to each other to construct the first input end of the first NOR gate and receives the stage transfer signal of the GOA unit circuit of the former N-1th stage; gates of the nineteenth P-type TFT and the twenty-second N-type TFT are electrically coupled to each other to construct the second input end of the first NOR gate and receives the global signal; a source of the nineteenth P-type TFT receives the constant high voltage level signal, and a drain is electrically coupled to a source of the twentieth P-type TFT; both source of the twenty-first N-type TFT and the twenty-second N-type TFT receives the constant low voltage level signal; drains of the twentieth P-type TFT, the twenty-first N-type TFT and the twenty-second N-type TFT are electrically coupled to one another to construct the output end of the first NOR gate and outputs the NOR Logic process result of the stage transfer signal of the GOA unit circuit of the N-1th stage and the global signal.

6. The CMOS GOA circuit according to claim 1, wherein the second NOR gate comprises a twenty-third P-type TFT,

a twenty-fourth P-type TFT, a twenty-fifth N-type TFT and a twenty-sixth N-type TFT; gates of the twenty-fourth P-type TFT and the twenty-fifth N-type TFT are electrically coupled to each other to construct the first input end of the second NOR gate and receives the first clock signal; gates of the twenty-third P-type TFT and the twenty-sixth N-type TFT are electrically coupled to each other to construct the second input end of the second NOR gate and receives the global signal; a source of the twenty-third P-type TFT receives the constant high voltage level signal, and a drain is electrically coupled to a source of the twenty-fourth P-type TFT; both source of the twenty-fifth N-type TFT and the twenty-sixth N-type TFT receives the constant low voltage level signal; drains of the twenty-fourth P-type TFT, the twenty-fifth N-type TFT and the twenty-sixth N-type TFT are electrically coupled to one another to construct the output end of the second NOR gate and outputs the inverted clock signal.

7. The CMOS GOA circuit according to claim 1, wherein in the GOA unit circuit of the first stage, the first input end of the first NOR gate receives a circuit start signal.

8. A CMOS GOA circuit, comprising a plurality of GOA unit circuits, which are cascade connected as multiple sequentially-arranged stages;

wherein N is set to be positive integer, and the GOA unit circuit of an Nth one of the multiple stages comprises: an input control module, a latch module electrically coupled to the input control module, a signal process module electrically coupled to the latch module, an output buffer module electrically coupled to the signal process module and a storage capacitor electrically coupled to the latch module and the signal process module;

the input control module receives a stage transfer signal of the GOA unit circuit of an N-1th stage, which is one of the multiple stages that is immediately previous of the Nth stage, a first clock signal, a global signal, a constant high voltage level signal and a constant low voltage level signal; the input control module comprises a first NOR gate and a second NOR gate; a first input end of the first NOR gate receives the stage transfer signal of the GOA unit circuit of the N-1th stage, and a second end receives the global signal, and an output end outputs a NOR Logic process result of the stage transfer signal of the GOA unit circuit of the N-1th stage and the global signal; a first input end of the second NOR gate receives the first clock signal, and a second end receives the global signal, and an output end uses a NOR Logic process result of the first clock signal and the global signal to be a first inverted clock signal to be outputted; the input control module inverts the NOR Logic process result of the stage transfer signal of the GOA unit circuit of the N-1th stage and the global signal to obtain an inverted stage transfer signal, and inputs the inverted stage transfer signal into the latch module;

the latch module comprises a first inverter, and input end of the first inverter is inputted with the inverted stage transfer signal, output end outputs the stage transfer signal; the latch module latches the stage transfer signal;

the signal process module receives the stage transfer signal, a second clock signal, the constant high voltage level signal, the constant low voltage level signal and the global signal, and is employed to implement NAND logic process to the second clock signal and the stage transfer signal to generate a scan driving signal of the

19

GOA unit circuit of the Nth stage; implements NOR Logic process to the global signal with a result of implementing AND logic process to the second clock signal and the stage transfer signal to realize that the global signal controls all the scan driving signals of respective stages raised up to high voltage levels simultaneously;

the output buffer module comprises a plurality of second inverters which are sequentially coupled in series, which are employed to output the scan driving signal and to increase a driving ability of the scan driving signal;

one end of the storage capacitor is electrically coupled to a node between the latch module and the signal process module, and the other end is grounded, and employed to store a voltage level of the stage transfer signal; the global signal comprises a single pulse, and as the single pulse is high voltage level, all the scan driving signals of the respective stages are controlled to be raised up to high voltage levels at same time, and meanwhile, both the first NOR gate and the second NOR gate outputs low voltage levels to control the inverted stage transfer signal to be high voltage level, and the first inverter in the latch module is employed to pull down voltage levels of the stage transfer signals of the respective stages to clear and reset the stage transfer signals of the respective stages;

wherein the input control module further comprises a first P-type thin film transistor (TFT), a second P-type TFT, a third N-type TFT and a fourth N-type TFT, which are sequentially coupled in series; a gate of the first P-type TFT receives the first inverted clock signal, and a source receives the constant high voltage level signal; both gates of the second P-type TFT and the third N-type TFT are coupled to the output end of the first NOR gate; the drains of the second P-type TFT and the third N-type TFT are coupled to each other and output inverted stage transfer signal; a gate of the fourth N-type TFT receives the first clock signal, and a source receives the constant low voltage level signal;

the latch module further comprises a fifth P-type TFT, a sixth P-type TFT, a seventh N-type TFT and an eighth N-type TFT, which are sequentially coupled in series; a gate of the fifth P-type TFT receives the first clock signal, and a source receives the constant high voltage level signal; both gates of the sixth P-type TFT and the seventh N-type TFT receives the stage transfer signal; the drains of the sixth P-type TFT and the seventh N-type TFT are coupled to each other and electrically coupled to the drains of the second P-type TFT and the third N-type TFT; a gate of the eighth N-type TFT receives the first inverted clock signal, and a source receives the constant low voltage level signal;

the signal process module further comprises: a ninth P-type TFT, and a gate of the ninth P-type TFT receives the global signal, and a source receives the constant high voltage level signal; a tenth P-type TFT, and a gate of the tenth P-type TFT receives the stage transfer signal, and a source is electrically coupled to the drain of the ninth P-type TFT, and a drain is electrically coupled to a node; an eleventh P-type TFT, and a gate of the eleventh P-type TFT receives the second clock signal, and a source is electrically coupled to the drain of the ninth P-type TFT, and a drain is electrically coupled to the node; a twelfth N-type TFT, and a gate of the twelfth N-type TFT receives the stage transfer signal, and a drain is electrically coupled to the node;

20

a thirteenth N-type TFT, and a gate of the thirteenth N-type TFT receives the second clock signal, and a drain is electrically coupled to the source of the twelfth N-type TFT, and a source receives the constant low voltage level signal; a fourteenth N-type TFT, and a gate of the fourteenth N-type TFT receives the global signal, and a source receives the constant low voltage level signal, and a drain is electrically coupled to the node;

wherein the first NOR gate comprises a nineteenth P-type TFT, a twentieth P-type TFT, a twenty-first N-type TFT and a twenty-second N-type TFT; gates of the twentieth P-type TFT and the twenty-first N-type TFT are electrically coupled to each other to construct the first input end of the first NOR gate and receives the stage transfer signal of the GOA unit circuit of the N-1th stage; gates of the nineteenth P-type TFT and the twenty-second N-type TFT are electrically coupled to each other to construct the second input end of the first NOR gate and receives the global signal; a source of the nineteenth P-type TFT receives the constant high voltage level signal, and a drain is electrically coupled to a source of the twentieth P-type TFT; both source of the twenty-first N-type TFT and the twenty-second N-type TFT receives the constant low voltage level signal; drains of the twentieth P-type TFT, the twenty-first N-type TFT and the twenty-second N-type TFT are electrically coupled to one another to construct the output end of the first NOR gate and outputs the NOR Logic process result of the stage transfer signal of the GOA unit circuit of the N-1th stage and the global signal;

wherein the second NOR gate comprises a twenty-third P-type TFT, a twenty-fourth P-type TFT, a twenty-fifth N-type TFT and a twenty-sixth N-type TFT; gates of the twenty-fourth P-type TFT and the twenty-fifth N-type TFT are electrically coupled to each other to construct the first input end of the second NOR gate and receives the first clock signal; gates of the twenty-third P-type TFT and the twenty-sixth N-type TFT are electrically coupled to each other to construct the second input end of the second NOR gate and receives the global signal; a source of the twenty-third P-type TFT receives the constant high voltage level signal, and a drain is electrically coupled to a source of the twenty-fourth P-type TFT; both source of the twenty-fifth N-type TFT and the twenty-sixth N-type TFT receives the constant low voltage level signal; drains of the twenty-fourth P-type TFT, the twenty-fifth N-type TFT and the twenty-sixth N-type TFT are electrically coupled to one another to construct the output end of the second NOR gate and outputs the inverted clock signal.

9. The CMOS GOA circuit according to claim 8, wherein the output buffer module comprises three second inverters which are sequentially coupled in series, and input end of one of the three second inverters directly next to the signal process module is electrically coupled to the node, and output end of the second inverter farthest to the signal process module outputs the scan driving signal.

10. The CMOS GOA circuit according to claim 9, wherein the second inverter is constructed with a seventeenth P-type TFT coupled with an eighteenth N-type TFT in series, and gates of the seventeenth P-type TFT and the eighteenth N-type TFT are electrically coupled to each other to construct the input end of the second inverter, and a source of the seventeenth P-type TFT receives the constant high voltage level signal, and a source of the eighteenth N-type

TFT receives the constant low voltage level signal, and drains of the seventeenth P-type TFT and the eighteenth N-type TFT are electrically coupled to each other to construct the output end of the second inverter; an output end of the former second inverter is electrically coupled to input 5 end of a next one of the second inverters.

11. The CMOS GOA circuit according to claim 8, wherein the first inverter is constructed with a fifteenth P-type TFT coupled with a sixteenth N-type TFT in series, and gates of the fifteenth P-type TFT and the sixteenth N-type TFT are 10 electrically coupled to each other to construct the input end of the first inverter and are inputted with the inverted stage transfer signal, and a source of the fifteenth P-type TFT receives the constant high voltage level signal, and a source of the sixteenth N-type TFT receives the constant low 15 voltage level signal, and drains of the fifteenth P-type TFT and the sixteenth N-type TFT are electrically coupled to each other to construct the output end of the first inverter and outputs the stage transfer signal.

12. The CMOS GOA circuit according to claim 8, wherein 20 in the GOA unit circuit of the first stage, the first input end of the first NOR gate receives a circuit start signal.
